STRIP STORAGE ENVELOPE

Glen W. Offensend and Walter D. Vogt, Rochester, N.Y., assignors to Eastman Kodak Company, Rochester, N.Y., a corporation of New Jersey
Filed Mar. 10, 1961, Ser. No. 94,926
4 Claims. (Cl. 40—17)

This invention relates to a strip storage envelope and more particularly to an envelope which is adapted to slidably receive and store a plurality of film strips so that the strips may be selectively advanced from their normal storage position in the envelope to a position where images on the film strips may be viewed, and thereafter returned to the envelope.

The envelope of the present invention is especially useful in receiving and storing strips of microfilm. Indeed, this is the use for which the device was originally intended and for this reason it has been specifically illustrated in the drawings and will be described herein as it is adapted for this use. However, it will be apparent from the drawings and from the description which follows, that the strip receiving envelope of the present invention could be used with similar facility and advantages for storing any type of material which is used or usable in strip form.

The difficulties involved in retrieval of information which has been photographically recorded on film is one of the main obstacles to the more extensive utilization of microfilm for storage of documentary information. To retrieve information on roll film it is helpful to have a code system which must of necessity be quite complex to identify all of the information and a mechanism for advancing the film strip through a sensing station where the code can be interpreted and correlated so that the desired information may be located. Apparatus of this type are very expensive to manufacture and to maintain. Other systems have utilized short strips of microfilm which are received in or printed on small cards so that the cards may be positioned in a projection-type reader for viewing purposes. One difficulty presented by this latter system is that involved in the positioning of the card in the reader so that the desired image is projected on the viewing screen. Another difficulty is the scratching of the images on the card during handling and viewing. The envelope of the present invention provides an improved means for storing and handling film strips and has certain advantages over the other systems mentioned above. The envelope of the present invention comprises broadly a member having one or more strip receiving channels for selectively receiving one or more film strips respectively therein. According to another aspect of the invention, the member includes means for engaging each film strip when located in a channel in normal storage position therein, to releasably retain the film strip in that storage position. This reduces the possibility of the film strip partially falling out of the envelope and becoming damaged during handling and transporting of the envelope. Still another aspect of the invention is the providing of second means for engaging the film strips when moved to a position remote from their normal storage position in the envelope to thereby prevent the film strip from falling out or completely disengaging from the channel in the envelope. This eliminates the possibility of accidental loss of a film strip during handling of an envelope and prevents an inadvertent removal of a strip during use from its channel in an envelope.

The primary object of the present invention is, therefore, to provide an envelope for slidably receiving and for storing one or more strips of material.

Another object of the present invention is to provide

2

an envelope for slidably receiving and for storing strips in which the strips are releasably retained within the envelope so that they will not be inadvertently damaged during handling of the envelope.

Still another object of the present invention is to provide an envelope for slidably receiving and for storing strips in which the strips are locked to the envelope in such a way that the strips cannot be inadvertently removed from the envelope.

Yet another object of the present invention is to provide a device for slidably receiving and for storing one or more strips in which each strip is releasably retained within the envelope when located in a normal storage position therein and is further locked in the envelope so that it cannot be inadvertently disengaged therefrom when moved to a position remote from its normal storage position therein.

Another object of the present invention is to provide an envelope for slidably receiving and storing one or more strips, which is relatively simple to manufacture and to use, which can be formed of relatively inexpensive materials, and which is entirely satisfactory from the standpoint of its normal intended use.

Still other objects and advantages of the present invention will become readily apparent to those skilled in the art from the following description with reference to the drawings in which like characters denote like parts and wherein:

FIG. 1 is a top plan view showing the strip receiving envelope of the present invention and broken as indicated to facilitate the illustration thereof;

FIG. 2 is an exploded view of the envelope showing the various parts thereof;

FIG. 3 is a partial section view of the envelope taken along lines 3—3 of FIG. 1;

FIG. 4 is a section view of the envelope taken along lines 4—4 of FIG. 1 but showing the strip moved from its storage position; and

FIG. 5 is a section view similar to FIG. 4 but illustrating another embodiment of the present invention.

As shown in FIGS. 1 through 4 of the drawings, the strip receiving envelope of the present invention comprises an upper sheet 11, a lower sheet 13, and an intermediate sheet 15 which is formed with a plurality of strip receiving channels 17, 19, 21 and 23. The strip receiving channels are spaced from each other in the intermediate sheet 15 so that the distance between adjacent channels is equal. Each channel is slightly wider than the lateral width of the strip to be received therein and the thickness of the intermediate sheet 15 is slightly greater than the thickness of the strip so that the strip will be guided by the channel, but can slide freely therein. This is important when the envelopes are used in conjunction with storing microfilm because it is necessary to position the envelopes in a reading type projector and to move the selected film strip from within the envelope through a projecting station where the image or images carried on the microfilm are projected by the optical system of the projector onto the viewing screen. Thereafter, of course, it is necessary to return the film strip back into the envelope for storage until the next time it is to be used. If the channel is too small, the strip may jam or buckle when one attempts to slide it back into the envelope. During the period that the film strip is being stored in the envelope; that is, when it is located all the way down into the strip receiving channel in its "storage position," as shown in FIG. 1, it is desirable for the envelope to substantially enclose the strip to prevent scratching of the film strip and dust accumulation thereon.

Frequently, it is necessary to carry an envelope from one place to another and it is desirable that the strip or strips therein not fall out of their respective channels.

Accordingly, a detent 25 is formed in the lower sheet 13 adjacent to the end of each channel 17, 19, 21, and 23. Detent 25 is upstanding from the surface of the lower sheet and has an elevation which is greater than the thickness of the intermediate sheet 15 and may be sufficiently great to extend or partially extend through suitable apertures 27 formed in the upper sheet 11, see FIG. 3. The sheets 11, 13 and 15 are formed from thin sheets of e.g. paper, fibreboard, plastic, sheet metal or other material, or combinations thereof, and the detents 25 may be formed by embossing the lower surface of the sheet 13 or by any other well known method. Apertures 27 are of a size to permit the detent 25 to extend therethrough. The ends of the strips are punched with a hole 29 which, when the strip is in its storage position, is aligned with the detents 25. Because of the resiliency and flexibility of the strip and the materials of which the envelope is formed and because of the tolerances which are utilized in making the strip receiving channels 17, 19, 21, and 23 the strips can be pushed down into the respective channels and will snap over the upstanding detent 25 and into their storage position, where the detent extends through the aperture 29 in the strip as shown in FIG. 3. When so located, the strip is releasably held within the channel by the detent 25. Obviously, by exerting a slight force on the other end 30 of the strip, it may be intentionally pulled off of the detent 25 and thereafter is free to slide in the channel in which it is carried.

In order to facilitate the initial insertion of the strips into their respective channels, the lower sheet 13 adjacent to the entrant portions of the channels is removed for a short distance as at 41 and 45 so that adjacent portion the upper sheet 11 extends over the lower sheet and acts as a guide for the end of the strip during insertion. The recesses 47 are formed in the envelope at the entrant portion of each channel so as to expose a small portion of the surface of the ends 30 of the strips when the strips are in their storage position in the envelope. This allows the strips to be manipulated within the channel, either manually or by suitable engaging means provided in for example a viewing apparatus. As shown, in the drawings, the end 30 of each strip is provided with a hole 49 which is exposed by the recess 47 when the strip is in its storage position in the envelope. The hole 49 is adapted to receive a pin or catch, not shown, but which is provided in the viewing apparatus with which the envelopes of the present invention can be used and by means of which movement may be imparted a selected one of the strips. It is also desirable to provide a means for locating the envelope in the viewing apparatus so that any one of the channels may be aligned with the mechanism which engages and moves the film strip through the projection station. Accordingly, in the embodiment shown, apertures 51 are punched through the envelope at positions which do not interfere with the channels and which are located with respect to the channels such that when fixed on two locating pins, not shown, which are provided in the viewing apparatus, the envelope is selectively positioned with any one of the four channels located in operative relation to the pin of the strip advance mechanism of the viewing apparatus.

In addition to the detents 25, which as described above, releasably hold the strips in their respective channels, it is sometimes desirable to provide means for preventing the strips from being inadvertently removed from their respective strip receiving channels. One means by which this may be accomplished is illustrated in FIG. 5. The embodiment shown in FIG. 5 is identical in every respect to the one which has been described above and shown in the other figures of the drawing except that the end 31 of the strip which has the hole 29' formed therein, is folded over to form a section of increased thickness. The hole 29' extends through both thicknesses of the strip. The lower sheet 13' of the

envelope adjacent to the entrant portion of each strip receiving channel is folded back upon itself as at 53. Thus, when the strip is pulled from its storage position in the envelope, it freely slides in the channel until the folded end 31 of the strip engages and locks with the folded portion 53 of the envelope as illustrated in FIG. 5. It is possible, of course, to intentionally break the lock by exerting a considerable force on the strip. However, the illustrated construction will eliminate any unintentional removal of the strip from the envelope by an operator.

While only one embodiment of the present invention has been specifically shown and described many modifications thereof in addition to the one shown in FIG. 5 are possible and will become readily apparent to those skilled in the art from the foregoing description. For example, the detents 25 could be arranged to extend from the edge of the channel into a notch formed into the longitudinal edge of the strips. The section of increased thickness in the strips could be provided by attaching or forming a flange on the end of the strip. The number and position of the channels in the envelope can be varied with the requirement of a particular operation. All of the channels could open on the same end of the envelope. The folded over portion 33 in each channel could be merely an upstanding lug or other stop means for engaging the thickened part of the strips. The positioning apertures 43 could be notches, detents, flanges or buttons formed along either the longitudinal or lateral edges of the envelope and adapted to cooperate with the structure of the apparatus with which the envelope is to be used. Since these and other modifications could be made without departing from the novel concept of the present invention, the foregoing description is intended to be illustrative only and the scope of the invention is defined in the appended claims.

Having now particularly described our invention, what we desire to secure by Letters Patent of the United States and what we claim is:

- 40 1. A device for slidably receiving and storing a plurality of discrete strips, each having an opening which is spaced from the edges of the strip adjacent to one end thereof, comprising:
  - 45 (a) a member having a plurality of channels for receiving said plurality of strips respectively therein, said member being formed of three laminated plies;
    - (1) the inner one of which is provided with said plurality of channels which are open on at least one end to receive said strips, and
    - (2) the outer plies substantially enclosing said channels to protect the strips when positioned for storage in the channels, and
  - 50 (b) a plurality of detents formed in at least one of the outer plies to extend into the plurality of channels respectively, said detents being disposed adjacent to the end of said channels which is remote from said one open end and having an elevation sufficient to extend through the openings in said strips, when positioned for storage in said channels, to thereby prevent accidental sliding displacement of the strips from such position.
- 55 2. A device in accordance with claim 1 and further comprising:
  - 60 (a) means in each of said channels for engaging the strips when slidably moved therein to a position remote from said storage position, to prevent disengagement of the strips from said channels, and
  - 65 (b) means in said member associated with each channel for selectively locating any given channel a predetermined fixed distance from any given reference point.
- 70 3. A device in accordance with claim 2 and wherein said stop means comprises an element which protrudes into said channel a distance sufficient to engage said enlarged section and which overlaps that portion of said

member which defines one wall of said channel adjacent to said one open end thereof.

4. A device for slidably receiving and for storing an elongated strip bearing information to be viewed and having adjacent to one end thereof an opening which is spaced from the edges of the strip and an enlarged section longitudinally spaced along the strip from said opening, said device comprising:

- (a) a member having an elongate planar strip receiving channel which is open at one end and is dimensioned to receive said strip, said channel being substantially closed throughout its length and being sufficiently long to enclose the strip when located in a storage position therein; 10
- (b) a detent upstanding in said channel adjacent to the end thereof remote from said open end and disposed to engage in said opening when the strip is in said storage position to releasably retain the strip in said storage position, and
- (c) stop means located in said channel adjacent to the open end thereof for engaging the enlarged section 20

of said strip, upon sliding movement of the strip in the channel to a position remote from said storage position and wherein said information is exposed for viewing, to prevent disengagement of the strip from said channel.
